UNITED STATES PATENT OFFICE

KARL F. NYSTROM, OF CHICAGO, ILLINOIS, ASSIGNOR TO CAMEL COMPANY, OF CHICAGO, ILLINOIS, A CORPORATION OF ILLINOIS

HOUSE-CAR END DOOR

Application filed August 11, 1926. Serial No. 128,534.

This invention relates to rear end doors for house cars and among the objects of the invention may be mentioned the provision of a structure so designed as to closely fit its openings and effectively close the end of the car during the severe usage to which it is put and means for easily and effectively securing the door in closed position.

The invention comprises the novel structure and combinations hereinafter described and more particularly pointed out and defined in the appended claims.

In the accompanying drawings which illustrate a preferred embodiment of this invention and in which similar reference numerals refer to similar features in the different views:

Figure 1 is an end elevational view of a car involving this invention.

Figure 2 is a sectional view upon the line II-II of Figure 1.

Figure 3 is a sectional view upon the line III-III of Figure 1.

Figure 4 is an enlarged fragmentary sectional view taken upon the line IV-IV of Figure 1.

Figure 5 is a fragmentary part sectional and part elevational view illustrating certain features of construction adjacent a hinge connection.

Figure 6 is a fragmentary plan view illustrating a gusset hinge that may be used.

Figure 7 is a fragmentary sectional view illustrating an upper portion of the locking rod and a keeper for the doors.

Figure 8 is a view similar to Figure 7 illustrating a modification of such structure.

Figure 9 is an enlarged fragmentary sectional view illustrating a lower portion of the car and door and showing the manner in which the locking rod may be secured.

In referring to the drawings which illustrate one embodiment of this invention, there is shown in Figure 1 the rear end of a car which is closed by a pair of doors 1 and 2 involving this invention. In the present instance, these doors are shown as consisting of spaced walls 3 and 4 with suitable channel bars 5 therebetween against which the walls 50 are united or secured. Each door is secured

to a lateral margin of the door opening by a plurality of hinges 6 which may be of the gusset plate type.

The upper and lower margin of each door comprises a Z bar 7 (Figure 2) the respective flanges of which are secured to the opposed walls of the doors. A wooden bar 8 or the like is secured in the exterior angle of each Z bar 7. The lower bar 8 is bevelled at its lower surface as indicated at 9 to wedgingly fit within the door opening which is provided with a suitable sill member 10 having an upwardly sloping flange 11 within the door opening which cooperates with the bevelled or sloping surface 9 on the bar 8. A Z bar 12 which is secured to the upper margin of the door opening affords a seat for the upper wooden bar 8 which fits in the lower angle thereof as shown in Figure 2.

The inner walls 3 of the doors which are preferably made of metal are bent outwardly at their outer lateral margins as indicated at 13 in Figure 5, and they are secured to the outer wall 4. The portion 13 slopes outwardly and cooperates with an inwardly sloping flange 14 of a channel member 15 at the lateral margin of the door opening. It should be noted that the lateral margin 16 of each door extends beyond the offset portion 13 and normally abuts the channel member 15 whereby the weather is effectively excluded.

The inner wall 3 of the door is provided with an outwardly offset terminal 17 (Figure 4) at its inner margin which is secured to the outer wall 4. A vertical plate 18 is secured to the inner margin of the door 2. This plate has an inwardly sloping portion 19 which terminates in a form of trough 20.

The inner wall of the door 1 is also provided with an outwardly offset terminal 17' which is secured to the outer wall 4. A plate 21 is secured to the inner margin of the door 1 and is provided with a rearwardly sloping flange 22 having a bent terminal 23 which fits in the trough of the plate 18 whereby a weather tight joint is provided.

A vertical locking rod 24 is pivoted upon the door 1 and swings as indicated in dotted lines in Figure 1 for engagement with keepers 25 and 26 which are respectively secured

to the bottom and top portions of the car. The rod 24 consists of a flat plate 27 upon which a ribbed plate 28 is secured. The rib which is indicated by the reference 28^a tapers from a medial point toward the ends so that the ends are substantially flat for ready insertion under the keepers 25 and 26, as indicated by the shaded portion in Figure 4. The manner of pivoting the rod 24 to the door 1 is best illustrated in Figure 4. In referring to said figure it will be noted that a small filler plate 29 is secured adjacent the inner margin of the door 1 substantially midway of the top and bottom thereof. A bearing 30 having an outwardly offset conical bearing socket 31 which overhangs the filler plate 29 is secured thereon. A conical bearing 32 is located in said socket. A pivot bolt 33 extends through the bearing 32 and through a side flange of the rod 24 which extends under the overhanging bearing 32 and through the door 1 to which it is bolted. Obviously the bearing 32 will frictionally engage the rod 24 and may rotate or swing therewith, since it is rotatably mounted in said bearing socket.

In Figure 7 there is shown the keeper 26 having an underhanging flange or lip 26^a for engaging the projecting rib 24^b of a metal member 24^a secured to the top of the rod 24. Instead of the interengaging parts 24^b and 26^a as shown in Figure 7, the locking rod 24 and keeper 26 may be provided with interengaging beads 45 and 46 as shown in Figure 8. The bead 45 may be formed of rivet heads or the like, while the bead 46 may be formed by inwardly crimping the lower end of the keeper 26.

In Figure 9 is shown the manner of securing the lower end of the locking rod 24. It will be noted that the keeper 25 is provided with an inwardly overhanging flange or lip 25^a under which a foot 47 on the lower end of the rod engages. It should however, be understood any similar interengaging parts may be used. Due to the upper interlocking parts 24^b and 26^a and the lower interlocking parts 25^a and 47, the locking rod 24 also ties the upper and lower parts of the car together and serves as a tension member when the upper and lower parts of the car tend to spread apart, and as a compression member when such parts tend to come together or contract.

Mechanism has been provided for swinging the rod 24 to bring its ends under the keepers 25 and 26 or remove the same therefrom. This mechanism consists of a bell crank lever 34 (Figure 1) pivoted at its heel 60 to the door 1, preferably adjacent the lower portion thereof. One arm of this bell crank lever is connected by means of a link 35 with the rod 24. The other arm of this bell crank lever is in the form of an operating handle 65 36 having a slot for receiving a hasp 37 where-

by the lever may be sealed or locked in closed position against operation. When the locking means are removed and the handle 36 is freed from the hasp, it may be swung as shown in dotted line position to swing the rod 24 for unlocking the doors. To limit the swinging movements of the rod 24, proper stop clips 38 may be placed upon the doors as shown in Figure 1, to prevent the swinging movement of the rod beyond such stops.

The door 2 is provided with a locking bolt 39 slidably maintained in a suitable bearing 40. This bolt is adapted for engaging a keeper 41 on the bottom of the car whereby the door may be latched after it has been closed and before the door 1 has been closed and the rod 24 operated. This latter bolt will also secure the lower portion of the door in proper position against the car.

In order to tie the side plates of the car to the end plate above the aforescribed doors, a pair of angle clips 42 are secured to each side plate adjacent the ends thereof. An angular gusset plate 43 has a horizontal flange 43^a riveted to the outstanding flanges of the angle clips and a depending flange 43^b which is riveted to the end plate 44 and to the Z bar 12, and terminates at the end of the end plate 44.

It will be appreciated that the particular construction heretofore described possesses excellent weathering features due to the bevels on the doors and the coaction of the front plates 19 and 21, and due to the spaced walls of the doors, they are sufficiently rigid to withstand the strain but nevertheless light to avoid excessive weight. At the same time, a novel operating mechanism for the locking rod has been provided and means whereby the mechanism can be locked against unauthorized use.

I am aware that many changes may be made, and numerous details of construction varied through a wide range without departing from the principles of this invention, and I therefore do not purpose limiting the patent granted hereon, otherwise than necessitated by the prior art.

I claim as my invention:

1. In a house car end construction comprising a pair of hinged doors having overlapping frontal margins, a swingable locking bar pivoted intermediate its ends to one door, keepers upon the upper and lower parts of said car for receiving the ends of said bar, said keepers and the ends of said bar having interlocking parts for tying the upper and lower parts of the car together.

2. In a house car having a pair of hinged doors with overlapping frontal margins, a keeper above said door, a second keeper below said door, each keeper having an overhanging lug, and a locking bar pivoted intermediate its ends to the overlapping door, and having parts engageable under said keepers by a

swinging movement and having parts engaging said overhanging lugs for tying the upper and lower parts of the car together.

- 5 3. In a house car end door construction comprising a pair of hinged doors having overlapping frontal margins, a swingable locking bar pivoted intermediate its ends to the overlapping door, the terminals of said locking bar having outwardly projecting lugs, keepers upon the upper and lower parts of the car for receiving the ends of said bar, each keeper having a horizontal portion and an inwardly directed lip spaced from said horizontal portion, the lugs on said swingable locking bar engaging under said lips for tying the upper and lower parts together whereby said bar becomes a tension member when said parts separate and a compression member when said parts approach each other.
- 10 15 20 In witness whereof I have hereunto subscribed my name.

KARL F. NYSTROM.
